ADJUSTABLE TELEVISION ANTENNA AND
SUPPORT THEREFOR
Carl B. Roecken, 1202 Jefferson St. NW.,
Washington, D.C.
Filed Nov. 20, 1964, Ser. No. 416,182
1 Claim. (Cl. 343—823)

This invention relates generally to improvements in antenna units for receiving television signals and is directed particularly to a new and novel antenna construction designed for indoor use.

This application is a continuation-in-part of my application Serial No. 211,943, filed July 17, 1962, for Adjustable Television Antenna and Support Therefor, now abandoned, and which was in turn a continuation-in-part of my prior application Serial No. 473,932 for Adjustable Television Antenna, filed December 8, 1954, now abandoned.

It is generally conceded that antennas designed for receiving both broadcast and television signals, function most efficiently when outside a building and when located at a substantial elevation.

Antennas intended for outdoor use have been designed in many different forms and in the installation of the same the customary practice is to set up the antenna on the roof of a building or in some other elevated location and in this operation the antenna is customarily shifted or turned or otherwise set or placed until a position is reached at which the signal or signals come in with the greatest strength, after which the antenna is fixed against further movement. When so fixed the antenna functions to collect or pick up electric signal impulses coming from a particular direction, in greater strength than signals or impulses coming from other directions.

In the light of the foregoing it is a particular object of the present invention to provide a new and novel type of adjustable antenna designed for indoor use and so constructed as to function will all the efficiency of the conventional or commoner types of antennas such as the straight and folded dipole antennas and the like.

Another object of the invention is to provide a long range or long distance antenna designed particularly for rural use wherein the novel design gives to it characteristics whereby signals from relatively great distances can be picked up even though the antenna structure is designed solely for indoor use.

More specifically the present invention has for an object to provide a new and novel antenna structure of a relatively high degree of efficiency combined with small size whereby the structure can be placed in the room in which the television receiving apparatus is located, upon such apparatus or upon any other suitable support.

The invention will be best understood from a consideration of the following detailed description taken in connection with the accompanying drawings forming a part of the specification, with the understanding that the invention is not confined to a strict conformity with the showing of the drawings but may be changed or modified so long as such changes or modifications mark no material departure from the scope of the appended claim.

In the drawings:

FIG. 1 is a view in side elevation of an adjustable antenna structure constructed in accordance with the present invention, the extensible poles forming a part thereof being collapsed to minimum length and hidden from view.

FIG. 2 is a bottom plan view of the structure showing the parallel extensible or telescoping collector poles reduced to minimum length.

FIG. 3 is a sectional view taken substantially on the line 3—3 of FIG. 1 and on an enlarged scale, showing

2

details of construction, portions of the globes being in elevation.

FIG. 4 is a sectional view taken transversely of the structure substantially on the line 4—4 of FIG. 1.

FIG. 5 is a sectional view taken transversely of the base structure substantially on the line 5—5 of FIG. 1.

FIG. 6 is a detailed view, in perspective, looking at the underside of the base structure and at one end showing the partial extension of one of the collector poles.

10 FIG. 7 is a view in perspective of a modified construction of the invention in combination with a novel supporting structure therefor.

15 FIG. 8 is a horizontal section substantially on the line 8—8 of FIG. 7 and looking upwardly toward the underside of the top portion of the supporting band or structure and of the antenna structure.

FIG. 9 is a partial section taken substantially on the line 9—9 of FIG. 8.

20 Referring now more particularly to the drawings, the numeral 10 generally designates the base member for the antenna structure. The base member is here shown as comprising a suitable length of insulation material of suitable character, such as wood, fiber, fiber glass, plastic, such as polyethylene, hard rubber, the insulation material popularly known as Bakelite, glass or any other material having insulating qualities.

25 The insulation body 12 forming a part of the base structure is, as most clearly shown in FIGS. 4, 5 and 6 of rectangular cross section and in use, has the wide faces thereof horizontally disposed thereby providing the top face or surface 14 and the bottom face or surface 16.

30 The bottom face 16 of the body 12 has thereon and extending throughout the length thereof, adjacent to each side edge, a strip 18 which is preferably of sponge rubber or some other suitable soft material and which provides the spaced parallel supporting flanges of non-scratching material which rest upon the top of the radio or television cabinet or any other surface upon which the antenna may be placed. These flanges or strips 18 also will provide between them the longitudinal downwardly opening channel 20 in which the hereinafter described elements of the antenna structure are positioned.

35 While the illustration and description designate a base structure having the body part 12 of one type of material and the strips 18 of another type of material, such as sponge rubber or the like, the entire base member may be made or formed by the process of extrusion where the selected material, such as polyethylene plastic or other plastic, is of a nature to permit its formation in this manner.

40 At approximately the center of the elongate body 12, one side of the body has formed therein the short transversely directed passage 21 which at its inner end terminates in the downwardly directed portion 22 which opens into the channel 20 as best seen in FIG. 4 and the purpose 45 of which passage will be hereinafter set forth.

45 Disposed within the channel 20 are the two spaced parallel elongate collector poles 23 and 24. Each of these collector poles comprises the telescopically associated elements 25, 26 and 27, the element 25 being tubular and 50 having the element 26 slidably extended thereinto from one end and the element 26 also being tubular and having slidably extended thereinto the third element 27 which may be tubular or a solid metal bar as may be desired. As shown these collector poles 23 and 24 are disposed in

55 spaced parallel relation each adjacent to the inner side of one of the strips or flanges 18 and is secured against the under face 16 of the body 12 in a suitable manner as, for example, by the use of the staples 28 illustrated in FIG. 5.

60 It will also be seen that the collector poles 23 and 24 are in reversed relation one with the other by which is meant that the slidable sections 26 and 27 of one pole are at the end of the tubular element 25 thereof opposite

from the end of the tubular element 25 of the other pole from which the extensible elements 26 and 27 project.

As will be readily apparent when the telescoping collector poles 23 and 24 are fully telescoped or reduced to minimum length they will be located entirely within the channel 20 between the ends thereof, but the length of each of the collector poles may be increased or extended as will be readily apparent particularly upon reference to FIG. 6 where the elements 26 and 27 of one collector pole are shown partly drawn out. By lengthening or shortening these collector poles the signal characteristics of the antenna structure will be changed as is well understood by those versed in the art.

Mounted upon the top surface 14 of the body 12 adjacent to the ends of the body are upstanding signal impulse gathering or collecting units designated 20 and 30, each of which is electrically connected, in the manner herein-after set forth, with one of the extensible poles 23 or 24.

Each of the top collector units 29 and 30 comprises a helix or spiral, generally designated 31, of wire of suitable weight, which stands upright from the top of the body 12 and has a portion of the bottom convolution 32 bent to extend downwardly as indicated at 34, through a passage 35 in the body 12 and this downwardly extending portion 34 is then turned laterally as indicated at 36 and is electrically connected to that end of the adjacent tubular portion of a pole 24 or 25, which is opposite from the telescoped or extensible portions 26 and 27 thereof, as is clearly shown in FIG. 2.

The upper convolution 37 of the helix 31 is extended into the straight arm portion 38 which is directed toward the opposite collector or towards the transverse center of the antenna structure and is electrically connected to globular collectors arranged in the manner about to be described.

At the inner side of each of the wire coils 31 are two superposed metal collector globes 39 and 40. These globes are hollow and are formed of a suitable thin metal such as aluminum, copper or the like and interposed between the two superposed globes is a metal block 41.

Extending axially through the superposed globes 39 and 40 of each of the upper collector units 39 and 40 is a tie-bolt or rod 42, the lower end of which passes through an opening 43 in the body 12 and has a nut 44 threaded thereon and located in the recess 45 formed in the underside of the body. This tie-rod 42 also passes through the metal spacer block 41 located between the globes and projects at its top end beyond the top of the uppermost globe and has threadably secured thereon the metal knob or head 46. This head bears down upon the top of the uppermost globe 39 and draws the globes and the interposed block 41 tightly together.

The block 41 has a passage 41a therethrough for the reception of the tie-bolt or rod 42 and also formed through the spacer block to one side of the passage 41a and at right angles thereto, is a passage 47 through which extends the straight upper end portion of the adjacent helix or coil 31. Each metal spacer block 41 is also drilled and tapped at the proper location to receive a set screw 48 which projects into the adjacent passage 47 for binding engagement with the horizontal portion 38 of the adjacent coil to secure and electrically connect the parts together.

The collector globes 39 and 40 are preferably longitudinally grooved, the grooves being relatively closely placed and the portions between the grooves being outwardly bowed or rounded whereby the effective collecting surface area becomes relatively large as compared with a globe of approximately the same size where the wall surface may be smooth. However, a smooth surfaced globe or a non-grooved or non-fluted wall may be employed if desired.

The tie-bolts or rods 42 may be formed of any suitable material, preference being had for a plastic rod of the synthetic known under the trade name Plexiglas which is

a thermal plastic poly(methyl methacrylate), or a metal such as aluminum or other suitable material.

The numeral 49 designates a portion of a conventional signal lead-in cable of the type commonly used in connection with television receivers and embodying the two spaced parallel wires 50. An end of this cable 49 is extended into the passage 21 in the base body 12 in the manner shown in FIG. 4 and the ends of the wires 50 are each electrically connected in a suitable manner as, for example, by means of the nut and bolt assemblies 51 shown in FIG. 4 to the outer tubular portion 25 of an extensible collector pole 23 or 24 as is shown in FIG. 2. Thus it will be seen that each of the top collector units 29 or 30 is electrically connected through the coils forming a part thereof with one of the collector poles or units 23 or 24 located upon the underside of the base body 12.

While there has been illustrated in FIG. 4 a nut and bolt assembly 51 in which the bolt is shown extending through the outer tubular element 25 of the pole it will be readily understood that any other means may be employed for connecting the wire ends 50 to these poles as by soldering or welding and in this case the inserted telescoping portions, or elements 26 and 27 may be made of materially greater length, approximately equalling the length of the outer elements 25, as will be readily seen.

FIGS. 7, 8 and 9 illustrate the other embodiment of the invention together with a novel supporting structure with which either of the embodiments of the antenna is designed to be used.

In the second form or embodiment of the antenna structure, which is generally designated 110, the base 112 comprises a relatively long body formed of one of the materials having electrical insulating properties as herein-before specified.

The base body has the relatively flat top 114 and upon the underside there are secured in longitudinally extended parallel spaced relation the strips 118 of a suitable soft material such as sponge rubber or the like or the body may be extruded, as before stated. There is, accordingly, formed between the strips of material the channel space 120 which extends longitudinally of the base as shown in FIG. 8.

Adjacent to the transverse center of the body 114 there is formed the transversely directed passage 121 which, at its inner end, terminates in the downwardly opening recess 122, located between the strips 118 or, in other words, in the channel 120. Located within the channel and extending lengthwise thereof are the two spaced parallel, elongate electric current or wave collectors 123 and 124. These, like the collectors 23 and 24 herein-before described, are made up of telescopically associated elements 125, 126 and 127 whereby the length of the collectors or antenna poles 123 and 124 may be changed as required.

The collector poles 123 and 124 are secured within the channel space 120 by suitable means such, for example, as staples 128 and the collector poles lie above the plane of the bottom surfaces of the strips 118, as is clearly shown in FIG. 9, whereby when the antenna structure is placed upon a supporting body such as a table surface or the like or the hereinabove described stand or support shown in FIG. 7, the poles will not contact the underlying surface.

The collector poles in this modified construction, have flattened inner end portions 123a and 124a, which are positioned or located adjacent to the opening 122 and are secured to the base by suitable means such as screws 125a which additionally function as wire securing terminals.

The numerals 129 and 130 generally designate signal impulse gathering or collector units, each of which is electrically connected, as hereinabove set forth, with an inner end of one of the collector poles 123 or 124.

Each collector unit embodies in its structure an upstanding helix or spiral, generally designated 131, of wire of suitable weight, and these units 129, 130 and 131 stand

upright upon the top surface 114 of the base body 112 as shown.

The bottom convolution 132 of each of the spirals has a downwardly extending portion 134 which passes through a passage 135 in the base and continues in the long portion 136, in the passage 120 to and is secured by one terminal screw 125a as is clearly shown in FIGS. 8 and 9. Accordingly the bottom end of each spiral is electrically connected with an end of one of the collector poles 123 or 124.

The collector units 129 and 130 each comprises two hollow metal bodies 139. These hollow metal bodies are substantially globoid or more specifically are of ellipsoidal form and are positioned with their long axes vertically as shown so that the long axes of each pair of bodies 139 are aligned. In other words, each pair of bodies 139 has a common vertical long axis and the two bodies of each pair are positioned one upon the other as shown in FIGS. 7 and 9, the bodies being flattened at their ends as indicated at 140.

The flattened ends of the two bodies of each pair have openings 140a therethrough and there are interposed between the adjacent ends of each pair of bodies, the two metal washers or separators 141.

Extending through and on the long axis of the superposed ellipsoidal bodies 139 of each pair, is the long securing bolt 142 of fiber, metal or plastic, the lower end of which passes through an opening 143 in the base body 112. The bottom end of the bolt 142 is screw threaded as shown and it has threaded thereon, upon the underside of the base body, the securing nut 144, which is located in a suitable recess 145 in the body 112.

The top end of the bolt 142 of each pair of bodies 139, likewise has threaded thereon the securing nut 146. Thus the two bodies can be drawn tightly together in their vertical end to end assembly.

As best illustrated in FIG. 9, the top end or top convolution of each coil is extended into the straight terminal part 138 which part is located between and is in electrical connection with the metal washers 141 of the adjacent pair of collector bodies 139.

It will be seen from the foregoing that each pair of the ellipsoidal hollow metal collector bodies 139 is electrically connected to and through the adjacent coil 131, with an end of one of the extensible collector rods 123 or 124.

The numeral 149 generally designates a portion of the conventional signal lead-in cable, each of the two parallel wires 150 of which is electrically connected to one of the poles 123 or 124 by means of a screw terminal 125a.

The antenna structures hereinabove described and illustrated in the drawings are designed to be placed upon a suitable supporting surface without in any way marring such surface even though the antenna structure may be moved thereon.

Where a convenient flat supporting surface may not be available there is provided a novel supporting stand designed to hold the antenna structure and also designed so that it may be turned or moved as may be necessary to position it in the most desirable location.

The antenna carrier or support is generally designated S.

The support comprises a base 200 from which rises an extensible standard 202 made up of a number of sections designated 203, 204, and 205.

The sections 203 and 204 are tubular and are telescoped one into the other as illustrated while the upper section 205 may be tubular or solid and is telescoped into the tubular section 204 as shown and suitable means is provided for securing the several sections in a desired adjusted relationship. Such securing means may be in the form of winged set screws 206.

The top end of the upper section 205 has a head 207 mounted thereon and this head carries a frame structure which is generally designated 208 and with which is attached to a central plate 209, supported upon the head 207 by a screw member 210 which is threaded into the

head 207 through a suitable opening in the plate 209. By providing the opening in the plate, designated 207, of the desired size, the plate may turn freely around the threaded portion of the screw 210 so that the frame 208 may be rotated if desired. The screw 210 may be threaded down to tighten or secure the frame against turning, if desired.

The antenna supporting frame 208 comprises two side bars 212 which are disposed in spaced parallel relation and which have end portions 213 extending downwardly in convergent relation and fixed in a suitable manner to the plate 209. Thus these convergent end portions 213 of the frame, extending upwardly and outwardly from the supporting plate as illustrated, maintain the bars 212 in relatively widely spaced relation and in parallel relation as shown.

Each of the parallel bars 212 is formed midway between its ends with the downwardly extending or depressed portion 214. These downwardly depressed or offset portions 214 are of rectangular configuration and are of a suitable width between the side parts 215 thereof, to receive the base 12 or 112 of the antenna structure 10 and 110, as shown in FIG. 7.

When the antenna is in position upon the supporting structure S it will be insulated from the support by the insulation strips 118 or the insulation material of the base which strips, or the base, will rest upon the portions 214 of the support. It is intended that there shall always be an air space or insulation between the metal of the support S and the parts of the antenna structure.

It will be noted also, particularly with respect to the collector bodies 139, that the walls of the bodies are of relatively thin metal and that the cross-sectional dimensions are small as compared to the longitudinal dimensions and also it will be noted that these bodies are provided with a number of longitudinal grooves or flutes to thereby increase the surface area for collecting the electrical waves. The provision of a collecting area or surface area of similar extent in a body of smooth or unbroken surface contour would obviously require that the circumferential dimensions of the body be materially greater. However, a larger size body 139, of smooth form may be used, if desired, with equally good results.

The antenna structure and supporting structure therefor may be used in any part of a building either in a room in which the television receiver is located or in any other location and will pick up weak signals from great distances where conventional dipole antennas or antennas of other types would produce weak or ineffective signals.

The antenna structure, because of its novel compact design, in both of the disclosed embodiments, is particularly well adapted for use in apartments or in other locations where space may be at a premium. Also because of its novel construction, when so used in apartments or other buildings where considerable steel construction is employed, the globoidal or ellipsoidal form of the collector units 39 and 139, particularly where such units are fluted as shown and described, provide large signal collecting surface areas for picking up weak signals or signals which might be reduced in strength because of surrounding metallic bodies or structures.

In addition to the foregoing the invention is not only effective in picking up signals which are weakly received by antennas of other types but the resulting pictures have been found to have greater clarity or resolution than can be obtained by other antennas receiving the same broadcast signal.

While the scientific theory whereby these greatly improved results are had from the antennas herein described and claimed, is not entirely clear, it is believed that such results flow in great part from the association of the round surfaces of the receiving or accumulating bodies 39 and 139 associated in the novel manner illustrated, with the wire coils, whereby it is believed that a

transference of energy by induction is obtained which amplifies the received signals, and, as a result of this, the power delivered by the antenna circuit is greater than the sum total which would be collected and delivered by individual parts of the antenna structure. The provision of the conventional directional dipole units not only aids the signal collecting ability of these units or elements but also adds the other known advantages to be had from the same, by varying the lengths thereof.

Applicant has made extensive tests of his antenna in the forms herein disclosed in comparison with other types of antenna to be found on the market and in all instances the comparative tests showed the present claimed antenna structure to be equal in receiving capability to such other antennas and in the majority of cases the tests showed a definite outstanding superiority over other antenna structures. In making these comparative tests applicant's antennas and the ones selected for comparison were attached to the same television set or receiver and set to the same broadcasting station.

It has been found also by applicant that his antennas here disclosed when positioned directionally with respect to distant stations bring in signals strongly from distant stations whereas other types of antennas failed to bring in or only weakly brought in signals from the same distant stations. As the antenna structures of the present application are located closer or brought closer to the broadcasting station, the non-directional character of the antenna becomes more pronounced or, in other words, the antenna becomes more non-directional, it being highly

efficient in any position to which it may be oriented with respect to the broadcasting station.

As this invention may be embodied in several forms without departing from the spirit or essential characteristics thereof, the present embodiment is therefore illustrative and not restrictive, since the scope of the invention is defined by the appended claim rather than by the description preceding it, and all changes that fall within the metes and bounds of the claim or that form their function as well as conjointly cooperative equivalents are therefore intended to be embraced by the claim.

I claim:

15 An antenna structure comprising the new combination of a relatively flat base body of insulation material, a pair of elongate parallel metal telescoping di-pole arms each secured at one end to a side of the body at a point thereon adjacent to the point of securement of the other and extending in opposite directions, a pair of substantially globoid metallic collector units mounted upon an opposed side of said base body in relatively widely spaced relation to one another, an electric current conducting helical means electrically connecting each of said substantially globoid units with the said one end of one elongate collector, and means for attaching lead-in wires 20 to the said adjacent ends of said elongate collectors.
